(57) CLAIM

I claim the ornamental design for a bottle cap shaped table, as shown and described.

DESCRIPTION

FIG. 1 is a perspective view of the bottle cap shaped table showing my new design;

FIG. 2 is a front side view thereof;

FIG. 3 is a rear side view thereof;

FIG. 4 is a left side view thereof;

FIG. 5 is a right side view thereof;

FIG. 6 is a top plan view thereof;

FIG. 7 is a bottom plan view thereof;

FIG. 8 is a top plan view thereof with an exemplary logo; and,
FIG. 9 is a top plan view thereof with a second exemplary logo.

The broken lines depicting the exemplary logos in FIGS. 8-9 are for illustrative purposes only and form no part of the claimed design.
